PROJECTOR CASE OR THE LIKE

Erdick H. Nelson, Walworth, Wis.

Application June 30, 1951, Serial No. 15,728

Term of patent 14 years

(Cl. D61—1)

To all whom it may concern:

Be it known that I, Erdick H. Nelson, a citizen of the United States, residing at Walworth, Walworth County, Wisconsin, have invented a new, original, and ornamental Design for a Projector Case or the like, of which the following is a specification, reference being had to the accompanying drawing, forming a part hereof.

Fig. 1 is a perspective view of a projector case or the like showing my new design;

Fig. 2 is a side elevational view thereof, the opposite side being the same as that illustrated; and

Fig. 3 is an end elevational view, the opposite end being the same as that illustrated.

I claim:

The ornamental design for a projector case or the like, substantially as shown.

ERDICK H. NELSON.
